UNITED STATES PATENT OFFICE.

FRANCIS M. TINKHAM, OF SPRINGFIELD, MASSACHUSETTS.

COUCH-BED.

SPECIFICATION forming part of Letters Patent No. 738,582, dated September 8, 1903.

Application filed May 4, 1903. Serial No. 155,629. (No model.)

To all whom it may concern:

Be it known that I, FRANCIS M. TINKHAM, a citizen of the United States of America, residing at Springfield, in the county of Hampden and State of Massachusetts, have invented new and useful Improvements in Couch-Beds, of which the following is a specification.

This invention relates to couch-beds, and has special reference to a bed of this class in which the conversion from the couch form to the bed form is effected by the lateral extension of the parts, the object of the invention being to provide a laterally-extending bed-section which when drawn out to constitute the bed will locate the mattress or bed-bottoms of the two sections in the same horizontal plane, a further object of the invention being to improve the devices for effecting the extension of the bed-section to shift said section in its movement toward the couch-section, whereby it may be nested therewith in a different plane from that which it occupies in its extended position, said devices including means to lock the movable section of the couch either in a nested or in an extended position.

Having these objects in view, the invention consists in the construction described in the following specification and pointed out carefully in the claims forming a part thereof.

In the drawings forming part of this application, Figure 1 is an end elevation of a couch-bed construction embodying this invention with the sections nested. Fig. 2 is a similar view of the construction with the sections extended, certain parts being broken away. Fig. 3 is a sectional plan view of the mechanism whereby the bed-section is extended, the section through the posts having been taken on line 3 3, Fig. 1. Fig. 4 is a sectional plan view of the complete frame on line 4 4, Fig. 1. Fig. 5 is an enlarged end elevation of a portion of the posts and end rails on which the bed-bottom is supported. Fig. 6 is an enlarged perspective view of one end of one of the end rails on the couch-section.

This couch-bed construction consists, essentially, of two sections, one being stationary and the other movable relative thereto. The stationary section consists of the end frames *a* and *b*, and the mattress or bed-bottom *q*, supported on these end frames, transversely

between the legs of which are the end bars *n* and *u*, on which the mattress is directly applied.

Two side braces *g* and *h* extend between the two end frames near the floor, running in a straight line from the inside of the legs of one frame to a like point on the other. The above-described parts constitute the entire frame part of one of these sections. The other one comprises the end frames *i* and *j*, which are united by the side braces *k* and *m*, enough shorter than the side braces *g* and *h* to permit the end frames *i* and *j* to be located inside the frames *a* and *b*, as shown in the plan view, Fig. 4. The legs on one side of the frames and one side brace *m* in this figure show only in dotted lines, however, as the legs on the back side of the frames *i* and *j* are cut off, as seen in Fig. 2, to permit them to clear the side brace *h* when the section of the couch of which they constitute a part is drawn out from the first-described section, the side brace *k* being secured at or near the extremity of said shorter legs.

At a suitable height above the floor a mattress-bar *n* is secured to each of the frames *a* and *b* in any convenient manner. A portion of one of these bars is shown in Figs. 5 and 6. They are made of L-iron and are applied to said end frames with the horizontal web of the bar uppermost.

As clearly shown in Fig. 6, the vertical web is carried beyond the horizontal web at each end, and these ends *o* are turned back at right angles to the body of the bar, the extremities of said turned-back ends being secured to said frames. This construction provides means to offset said bars inside the end frames enough to permit the inner legs of the end frames to be located within said offset, as shown in Fig. 5, and it also prevents the movable section of the construction in which the end frames *i* and *j* are comprised from being separated from the stationary section and serves also as a stop to bring said first-named section into proper relation to the last-named section when the two sections are extended to constitute a bed. This offset in the mattress-bars is the same in the bars of both frames *a* and *b*, but only the bar on the frame *a* has been shown in the drawings.

The mattress-bar *n* on the end frame *b* ex-

tends in a straight line between the legs thereof without the offset and is in the same horizontal plane as the bar on the frame *a*. The outer edge of both of these mattress-bars is perforated with holes *p*, as shown in Fig. 6, through which the wires *q*, which constitute parts of the mattress, may be passed and secured. This mattress may be of any form capable of being supported on these bars 10 *n* and similar bars on the end frames of the movable section. This offset in the mattress-bar *n* on the end frame *a* further provides for the location of the elbow-levers by which the movable section of the couch is extended 15 in the plane located between the end frames *a* and *i*, this movable section being pushed outward simultaneously from both ends thereof by means of a rotatable rod or tube *r*, to the ends of which two arms *s* and *t* are secured, 20 the arm *t* being on that end next the frame *a*. (See Fig. 4.) This rod *r* is rotatably supported centrally of the end braces *d* and *e*, the arms *s* and *t* extending diagonally up to the inner upper corner of the end frames *i* 25 and *j*. These arms and the levers whereby they are made to swing the movable section of the couch outward and inward relative to the stationary section will be described farther on, and the manner of supporting the 30 movable section on the stationary section will first be described.

On the end frames *i* and *j* the mattress-bars *u* and *v* of L-iron are secured, (see Fig. 2,) similar in all respects to the bar *n* except that 35 there is no offset therein. They are attached to their frames, however, in inverted position as compared with the bars *n*—that is, with the horizontal web of the L-iron next to the horizontal web of the bar *n*—and the vertical 40 web extending upward instead of downward, as clearly shown in Fig. 5, the edge of the horizontal web of the bars *u* and *v* being perforated like the edge of the bar *n*. (Shown in Fig. 6.) This permits the location of the 45 two mattresses or bed-bottoms in close proximity to one another, as shown in Fig. 5, and greatly reduces the degree of vertical movement necessary to bring the bed-bottom of the movable section of the couch into the same 50 plane as that of the other bed-bottom.

Small metal bearing-wheels *x* are mounted on the vertical web of the bar *n* on each of the end frames *a* and *b*, the horizontal web of the frame being slotted to permit the peripheries of these wheels to extend above the plane 55 of said web, as shown in Figs. 1, 2, and 5, and these wheels support the movable section of the couch, the horizontal web of the mattress-bars *u* and *v* bearing thereon, as shown in 60 Figs. 1 and 5, when the movable section is nested within the stationary section, and in this position the outer legs of the frames *i* and *j* do not touch the floor. When this movable section, however, is extended, as shown in Fig. 65 2, then the mattress-bars run off the wheels and the ends thereof drop down onto the horizontal flange of the bars *n*, the outer legs of

the frames *i* and *j* resting on the floor, the mattress-bar on said movable section in this position being parallel with the bar *n* and the 70 plane of the two mattresses will be so nearly in the same plane that when the bed is made up no difference in the level of the two parts will be noticeable. To move this sliding section, two elbow-levers 2 and 3 on one side of the arm *t* and two other levers 4 and 5 on the other side of the arm *t* are connected together and to this arm and also to the legs of the frame *a*, as clearly shown in Figs. 1 and 2 in end elevation and in Fig. 3 in plan view. The 80 levers 2 and 5 are pivotally secured to the legs of the frame *a*, on opposite sides thereof, at 6 and 7, and the levers 3 and 4 are pivoted by one end, respectively, to the free ends of levers 2 and 5 and by their opposite ends to the 85 arm *t* at 8. The ends of the levers 2 and 5 where they are joined to the levers 3 and 4 are turned at an angle thereto, as shown at 9, and a pin 10 is secured in the end, projecting outwardly to provide a rest for the foot 90 to bear against to operate these levers. Preferably the arms *s* and *t* are made in two parts, the upper one, 12, being slidable on the other, as shown in Figs. 1 and 2, to the end that when the sliding section of the couch is moved 95 in or out the end of the arm may not project above the end frame, as would be the case were these arms in one piece and slotted at the point of its connection with their connection with the end frames. 100

In Figs. 3 and 4 it is shown that the end bars *d* and *e* are provided with two offsets, extending in opposite directions and indicated by 13 13 on each side of the center thereof, and the central offset is indicated by 14. The offsets 13, as shown in Figs. 1 and 2, provide room for the elbow of the levers 2 and 3 and 4 and 5 to pass the bar *d* when one pair or the other is flexed. The central offset 14 permits the location of the arm *t* in proper relation to the levers 2 and 3 and 4 and 5. The arrangement of these levers is such that when the movable section of the couch is nested in the stationary section the pair comprising 2 and 3 will be flexed and the other pair, comprising 115 4 and 5, will be extended, and by reason of the shape of the levers 2 and 5 the extended pair will be toggled, thus locking the movable section in an extended or in a nested position, pressure downwardly upon the pin 10 or the 120 joined ends of the levers being necessary to break their toggled relation. 125

I am aware that couch-beds have been constructed heretofore in which a laterally-movable section has been nested within a stationary section, and broadly no claim is made to this; but in the structure on which this application is based the sliding section of the couch is so located when nested in the stationary section that the plane of the wire mattress or 130 bed-bottom of the stationary section lies below that of the movable section, but when the latter is drawn out the two mattresses are in substantially the same plane.

Having thus described my invention, what I claim, and desire to secure by Letters Patent of the United States, is—

1. A couch-bed consisting of a stationary section and a movable section, mattress-bars secured to the end portions of each section, L-shaped in cross-section; the vertical webs of the bars on the stationary section extending downwardly, and those on the movable section extending upwardly; the said bars on the stationary section serving as supports for the movable section.
2. A couch-bed consisting of a stationary section comprising end frames resting on the floor, and mattress-bars extending transversely of the end frames, each of said bars having an offset therein in the direction of the other; a movable section comprising end frames, the inner leg of each of which is located within said offset; mattress-bars on the end frames of said movable section and extending in a straight line thereacross, said movable section being capable of nesting in said stationary section, the mattress-bars on the latter serving as supports for the movable section when in said nested position, together with means to move said movable section laterally to locate the mattress-bars thereon in the same plane as those on the stationary section.
3. A couch-bed consisting of two sections, one of which is stationary and the other of which is movable on said stationary section into and out of nesting position therewith; mattress-bars on the stationary section constituting a track for said movable section, and suitable wheels on which said movable

section is supported, whereby when said section is moved into nesting position it may be raised above the plane it occupies in an extended position.

4. A couch-bed consisting of two sections one of which is stationary and the other of which is movable on said stationary section into and out of nesting position therewith; end frames forming part of each section, and side braces extending between the end frames of the stationary section; the legs of the inner portions of the end frames of the movable section being cut off at a point above the plane of said side braces, mattress-bars on both sections located one above the other in the same vertical plane, whereby the inner end of the movable section may be supported on the stationary section.

5. A couch-bed consisting of two sections one of which is stationary and the other of which is movable on said stationary section into and out of nesting position therewith; end frames forming part of each section, a rock-shaft extending between the end frames of the stationary section, a vertically-disposed arm on each end of the rock-shaft, pivotally connected at the free ends thereof with the movable section, and toggle-levers on one end of the couch associated with one of said arms to throw it in either direction to move the movable section of the couch into or out of nesting position relative to the stationary section.
